UNITED STATES PATENT OFFICE.

HARRY F. HUGHES, OF NEW YORK, N. Y., ASSIGNOR TO PHILIP O'REILLY
AND JOHN O'REILLY, OF SAME PLACE.

DARK LANTERN.

SPECIFICATION forming part of Letters Patent No. 643,768, dated February 20, 1900.

Application filed July 13, 1899. Serial No. 723,677. (No model.)

To all whom it may concern:

Be it known that I, HARRY F. HUGHES, a citizen of the United States, and a resident of New York, (Brooklyn,) in the county of 5 Kings and State of New York, have invented certain new and useful Improvements in Dark Lanterns, of which the following is a specification, reference being had to the accompanying drawings, forming part of the same, in 10 which—

Figure 1 is a vertical sectional view on line 11 of Fig. 2, the shield shown in the closed position. Fig. 2 is a cross-sectional view on line 2 2, Fig. 1, viewed from the under side. Fig. 15 3 is a plan view looking upward after having removed the base when the parts are in the position they occupy, when the finger end of the lever is thrown to the right. Fig. 4 is a rear elevation of the lamp. Fig. 5 shows in 20 elevation a portion of the outer casing and the lamp-holding base. Fig. 6 is an under face view of the base, and Fig. 7 is a detail view in section of the joint between the lens-holder and the main casing.

25 The invention relates to dark lanterns; and it consists in devices for its operation and features whereby its purpose of retaining the light, except as it may be intentionally projected through the lens, is accomplished.

30 C is the casing, usually a cylindrical tin body blackened upon the outside. It has an opening O in the front closed by a door D, which is hinged at h to the case and secured by a catch c, closing over a lug l on the case. 35 The door also has an opening in it, in which is seated the lens-holder H, carrying the lens L. The door and lens-holder are not secured in the ordinary way by solder; but I first make a bead b in the holder of the shape and a little 40 larger than the opening in the door a short distance from the inner edge of the holder. Then the inner edge of the holder is inserted in the hole or opening in the door and pressed or flanged outward upon the inner face of the 45 surrounding edge of the material of the door, the result being a very strong joint that continually remains impervious to light.

50 S is the shield, which I prefer to also construct as a tin cylinder, just enough smaller than the case in diameter to turn readily therein. It has an opening O' in the side

corresponding in size and shape to that in the case.

At the top the lantern is provided with a cap K and the usual double hood or cowl k k'. 55

To operate the shield, I provide a compound lever. First, I provide a three-armed bracket or support, its arms a a' being together long enough to extend across the casing C and rest on the edge. Then when the cap K is placed 60 thereon and crimped into position the ends of said arms will be secured, and it will be held in place, resting upon the upper edge of the casing. The third arm a' extends backward, usually at right angles to the others, to a point 65 just within the line of the shield S. l' shows lugs struck up from the shield to form a socket for the end of the swinging lever L², which is pivoted at p, centrally of the lamp, in the three-armed support, but extends well beyond that point and is slotted at s, a point 70 beyond the pivot. L' is the finger-lever, extending through a slot in the case, pivoted at p² in arm a' and provided with a thumb-piece T at the outer end. Its inner end is turned 75 down as a finger f', which enters the slot s, though other forms of linking the two levers together might be adopted.

When it is desired to shut off the light, the thumb-piece is pressed to the left, the slotted 80 opposite end of course swinging to the right, and finger f', bearing against the wall of slot s, will force the slotted end of lever L² to the right, swinging it on its pivot, which of course carries its opposite end (engaging the shield) 85 around in the same direction as the thumb-piece, but with a much greater movement. The shield being engaged by the end of lever L² will be simultaneously carried around to close the opening in the case and shut off 90 the light, whereby a considerable movement of the shield is obtained with a very slight movement of the thumb and the size of the slot s' in the case for the passage of the lever is reduced to a minimum, being very close to 95 its pivot. The guard-hanger and handles are arranged at the rear of the case. First, I secure a bench or brace B to the case. At suitable distances from the case on either side I crease it into tubes t t' for holding the handles h', and midway between those tubes I form a depression d to receive the wire hanger 100

or hook h^2 . G is the guard, secured to the case at top and bottom and extending somewhat above and below the limits of brace B, but secured thereto, where they coincide usually with solder, the use of the continuous brace in combination with the guard resulting in much greater strength than mere side supports would furnish. A slot s^2 in guard G permits the lever L' to extend to a convenient point, and through an opening o the hook h^2 is inserted into the channel for it between guard G and the depression d in the bench. The lower end of the hook being turned backward, it will thereby be held securely in place. Any beam of light that might escape through slot s^2 will be stopped against the guard, and as slot s^2 in it is not in the line from the flame through slot s^2 there will be no escape of rays through slot s^2 . In assembling the parts the shield is introduced at the bottom of the casing, and a flange F being then turned inward on the casing it is retained therein thereby. The base B' is provided with a hollow bead b' and two notches n and the case with two lugs m. They pass down the notches n to the bead b' and upon the base being turned around enter the hollow bead, the device thereby constituting a covered bayonet-joint, secure and yet preventing the escape of light. On its under face the base is provided with feet r to raise it slightly from any flat surface, and in a depression within the line of the circle of the lamp-base I cut a series of draft-apertures v. The lamp U, slightly less in diameter than the case and raised from the bottom where it

is over the apertures v to provide draft-space, is preferably secured to that base and has the usual fount and wick-tube.

What I claim as my invention, and desire to secure by Letters Patent, is—

1. The combination of a casing having an opening therethrough, a shield adapted to close said opening, a lever pivoted within said case and engaging said shield, a second lever pivoted at one side of the first pivot, extending without the case and engaging the first lever at a point beyond its pivot on the side opposite to that on which the second pivot is located, whereby the swinging of the second lever will operate the first to cause the shield to cover or uncover the opening in the case.

2. The combination of a casing having an opening therethrough, a three-armed support located therein, two arms of which are secured to the case and extend across the central part of the case, a shield adapted to close said opening in the case, a lever engaging the shield, pivoted in the support centrally of the case, but extending beyond the pivot, a second lever pivoted in the third arm of the support, one end extending through the case and the other connected to the extension of the first lever.

Signed at New York, in the county of New York and State of New York, this 24th day of April, A. D. 1899.

H. F. HUGHES.
